United States Patent

Des. 241,980
Patented Oct. 19, 1976

241,980

HEART PACER

David L. Purdy, 629 School St., Indiana, Pa. 15701;
George J. McGovern, 251 Old Mill Road, Pittsburgh,
Pa. 15238; and Nicholas P. D. Smyth, 5316 Ports-
mouth Road, Washington, D.C. 20016

Filed Feb. 14, 1975, Ser. No. 549,925

Term of patent 14 years

Int. Cl. D24—02

U.S. Cl. D83—1 F

FIG. 4

FIG. 3

FIG. 2

FIG. 5

FIG. 1 is a view in side elevation of a heart pacer illustrating our new design;

FIG. 2 is a view in end elevation as seen from the direction of arrow II of the heart pacer shown in FIG. 1;

FIG. 3 is a view in end elevation as seen from the direction of arrow III of the heart pacer shown in FIG. 1;

FIG. 4 is a top plan view as seen from the direction of arrow IV of the heart pacer shown in FIG. 1; and

FIG. 5 is a bottom plan view as seen from the direction of arrow V of the heart pacer shown in FIG. 1.

We claim:

The ornamental design for a heart pacer, substantially as shown and described.
